TRIPPLICATE MANIFOLDING BOOK

Albert R. Lawson, Hamilton, Ontario, Canada, assignor to Appleford Paper Products, Ltd., Hamilton, Ontario, Canada

Application May 17, 1937, Serial No. 143,048

8 Claims. (Cl. 282—9)

My invention relates to improvements in triplicate manifolding books.

Heretofore triplicate manifolding books have been fabricated in various forms but they were found generally in two different rather distinct groups. In one group heavy duty carbon leaves were used successively through the successive manifolding sets to make the carbon copies. In the other group, which is of more recent origin, one time carbon leaves were provided in the number required in each set.

An object of this invention is to provide a book incorporating the advantages of each of these two groups and requiring less time to operate than the heavy duty carbon type of book and costing less money than the one time carbon type of book.

Another object is to provide a book of the character described in which one of the carbon leaves from each set may be retained within the book so as to provide a permanent record of each transaction recorded in the manifolding sets in the book.

Another object is to provide a book wherein each set includes at least two clean surfaced record leaves and one carbon leaf, and a heavy duty carbon leaf is bound in the book and is usable successively through successive manifolding sets. The carbon leaf which forms a part of each set is a one time carbon leaf and may be secured to one of the record leaves of the set so as to be detachable therewith from the cover and to form a part of the set even after the set has been detached from the carbon. This carbon leaf will itself be detachable from the set following detachment of the set from the cover.

Another object is to provide, in combination with a plurality of manifolding sets of the character described, a cover enclosing such sets and serving as a carrier for them and which cover has a heavy duty carbon leaf hinged thereto for swingable movement successively into successive manifolding sets.

Preferably the heavy duty carbon leaf is hinged to a longitudinal edge of the cover assembly and also preferably the cover includes a stop sheet which is adapted to be swung into position underneath successive manifolding sets and the heavy duty carbon leaf is hinged to one longitudinal edge of this stop sheet and is adapted to be swung into position within the set underneath which the stop sheet is disposed.

The heavy duty carbon leaf may, however, be hinged to a cover along a line other than the longitudinal margin of the stop sheet. It may be

hinged to the longitudinal margin of the back cover.

The book may be so arranged that the sets are numbered to be worked from the top down or from the bottom up, whichever way is most desirable. If worked from the bottom up the requirements as to disposition of the one time carbon leaves following use may be different from that if the book is worked from the top down.

The one time carbon leaf in each unit may be secured therein for detachment with the unit as heretofore described or may remain attached to the cover on detachment of the other leaves of the unit from the cover. Different methods of attachment are hereinafter shown and described.

Other objects, advantages, and meritorious features of my invention will more fully appear from the following description, appended claims, and accompanying drawings, wherein:

Figure 1 is a perspective of a book embodying one form of my invention.

Fig. 2 is a perspective of one of the manifolding units used in the form of book shown in Fig. 1.

Fig. 3 is a perspective of the particular type of cover used in the manifolding book shown in Fig. 1.

Fig. 4 is a perspective of one of the individual manifolding units which may be used in lieu of the unit shown in Fig. 2 in the form of book shown in Fig. 1.

Fig. 5 is a perspective of a modified form of cover which may be used alternatively in lieu of the cover shown in Fig. 3.

Fig. 6 is a perspective of a modified form of manifolding book wherein the cover shown in Fig. 3 is used, but the manifolding units differ from the manifolding units used in the book shown in Figs. 2 and 4.

Fig. 7 is a perspective of one of the manifolding units used in the book shown in Fig. 6.

Fig. 8 is a perspective of a book embodying a second modified form of construction.

Fig. 9 is a perspective of a single manifolding unit of the character used in the book shown in Fig. 8, and

Fig. 10 is a perspective of a single manifolding unit which may be employed in lieu of the one shown in the form of book shown in Fig. 8.

Figs. 1-4 illustrate one type of book except for the alternative character of the units shown in Fig. 4. The book in Fig. 1 comprises a cover made up of a back 20, a front cover 22 hinged to the back and adapted to fold thereover, and a stop sheet 24 hinged to the opposite end of the

5

35

40

45

50

55

back as shown. Within this cover are secured a plurality of manifolding units. Each of these units may be of the type shown in Fig. 2. The word "book" is intended to include a plurality 5 of superimposed manifolding sets adapted to be successively used whether the sheets are bound permanently within a cover comprising a front and back or whether they are merely arranged in superimposed relationship for successive em- 10 ployment.

In Fig. 2 the unit is made up of a sheet of paper folded along the perforated fold line 26 to provide a triplicate clean surfaced record sheet 28 and an original clean surfaced record sheet 30. 15 A clean surfaced duplicate record sheet 32 is likewise provided for each set. The triplicate record sheet 28 may be perforated along the line 29 to be separated from a stub portion 31 which will remain bound in the cover and the original clean 20 surfaced record sheet may of course be detached from the triplicate record sheet 28 by severance along the perforated line 26. The duplicate record sheet 32 may be provided with a perforated line of severance corresponding to the perforated 25 line of severance 29 of the triplicate record sheet, but as shown in Fig. 2 it is not so provided.

There is also provided in each unit a one time carbon sheet 34. This is a light weight tissue-like carbon carbonized on its lower surface only. 30 The end portion which is found in the book is preferably uncarbonized and provides a stub 35 and there is a perforated line of severance 36 along which the sheet 34 may be detached from the stub 35. The opposite end of the one time 35 carbon sheet is likewise uncarbonized as shown as 37 and projects beyond the end of the duplicate leaf 32 whether the book be open or closed. The carbonized side of the leaf 34 is not exposed for accidental contact by one manipulating the 40 book. If it is desired to detach the carbon leaves 34 from the book, either singly or a number at a time, one or a number of them can be gripped along their clean margins where they project beyond the duplicate record leaves and detached 45 by a quick pull. After the used margin and triplicate leaves have been detached from the book or from a set the clean surfaced projecting end of the carbon leaf 34 extending beyond the duplicate leaf may readily be grasped for detach- 50 ment of the carbon leaf. As shown in Fig. 2 this one time carbon sheet 34 has its stub 35 bound in the book along with the duplicate record sheet 32 and the stub 31 of the triplicate record sheet 28. It may be bound therein by wire 55 staples or stitching or in any other suitable manner.

In Fig. 4 the unit is of slightly different form. It differs from the unit shown in Fig. 2 only in 60 that the one time carbon sheet 34 is adhesively secured at 38 to the back of the original record sheet 30 so as to be detachable therewith upon detachment of the unit from the book. In this particular unit it will also be noted that the one 65 time carbon sheet is of the same character as shown in Fig. 2, that is, it is a light weight tissue sheet carbonized on the lower side only as it will be evidenced from the turned back corner. The duplicate record sheet, similarly to the duplicate 70 record sheet of Fig. 2, is shown as free from any perforation line so that it would remain normally a permanent part of the book as would the duplicate record sheet of the unit shown in Fig. 2. This duplicate record sheet might, however, 75 be provided with a perforated line of severance

similar to the line 29 provided in the triplicate record sheet 28.

The type of cover employed is that shown in Fig. 3 and in this type of cover there is a heavy duty carbon sheet 40 which is adhesively secured 5 as at 42 to a longitudinal margin of the stop sheet 24. This adhesive securing is here shown as attained by the employment of a piece of adhesive tape 44 overlying the folded over edge of the carbon sheet and the adjacent portion of the stop sheet. 10

The type of cover shown in Fig. 5 differs from the cover shown in Fig. 3 in that the cover of Fig. 5 is not provided with a stop sheet. It has a back 29 and a front cover 22 as does the cover 15 shown in Fig. 3. It is then provided with a heavy duty carbon sheet 40 secured by a strip of adhesive 44 to the underside of the margin of the back as shown and as described in connection with the construction of Fig. 3. This heavy 20 duty carbon sheet would be carbonized on one side only as shown by the turned over corner portion 41.

The type of book shown in Fig. 6 differs from the one shown in Fig. 1 in the construction of the 25 individual manifolding units. The cover is of the type shown in Fig. 1 and more particularly illustrated in Fig. 3. The manifolding unit, however, includes only three leaves. In the Fig. 2 unit there are three clean surfaced record leaves and 30 a one time carbon leaf. In the unit shown in Fig. 7 there are two clean surfaced record leaves, being an original record leaf 30 and a triplicate record leaf 28. These record leaves form part 35 of the same sheet. The original record leaf is folded along the perforated fold line 26 to overlie the triplicate as shown. The triplicate record leaf has a stub 31 which is separated from the main portion of the leaf by a perforated line of severance 29. The one time carbon leaf is 40 indicated as 34. It is somewhat similar to the one time carbon leaf shown in Fig. 2 in that it has a stub 35 which is adapted to be bound in the book in conjunction with the construction shown in Fig. 2. It will be noted that this mani- 45 folding unit differs from the one in Fig. 2 only in the omission of the clean surfaced duplicate record leaf of the construction shown in Fig. 2. In the construction shown in Fig. 7 the one time carbon leaf 34 being carbonized on the lower 50 surface only is very lightly carbonized and has an upper surface which is sufficiently clean and opaque and free from carbon to serve as a record surface and this sheet serves as a record leaf. This sheet may form a permanent part of the 55 cover. In other words, it may not at any time be separated from the cover. In Fig. 7 it is not shown as provided with a line of severance to permit of its separation. To this extent it also differs from the one time carbon sheet of Fig. 2 60 in that the one time carbon sheet of Fig. 2 is shown as provided with a line of perforation 36 though it need not be so formed. Obviously, also, the one time carbon sheet 34 of Fig. 7 might be provided with a line of perforation to separate 65 it from the stub 35 if it was so desired. It is the carbon unit of Fig. 7 that is employed in the book shown in Fig. 6.

In the form of book shown in Fig. 8 the cover 70 resembles that of Fig. 3 except that the heavy duty carbon sheet 40 is not attached to the stop sheet 24 but is bound in the cover itself as shown in Fig. 8. This heavy duty carbon sheet 40 has a stub which is bound in the cover with the stubs of the record sheets. The several mani- 75

5 folding units may be of the character shown in Fig. 9 or of the character shown in Fig. 10. In Fig. 9 a record sheet is folded along the line 26 to form the triplicate and original clean surfaced record sheets 28 and 30 respectively which is similar to the constructions described in conjunction with Figs. 2 and 7. The triplicate record sheet 28 has a stub 46 spaced from the remainder of the sheet by a perforated line 10 of severance 48. There is then a second perforated line of severance 50 spaced below the line of severance 48 forming an intervening subsidiary stub portion between such two lines of severance to which the stub 35 of the one time carbon sheet 34 is adhesively secured by a line of adhesive 52. This one time carbon sheet is rolled back in the construction shown in Fig. 9 to show carbon on the lower surface of the sheet and the adhesive coated stub portion 35.

20 It is apparent that in this construction the one time carbon sheet would be detachable with the triplicate sheet 28 when such triplicate sheet was detached from its own stub in the removal of the unit from the book. It is also then apparent that upon severance of the triplicate sheet along the perforated line 50 that the one time carbon sheet and the triplicate sheet would be disconnected for separate distribution.

25 If the construction shown in Fig. 10 is employed it will be found to differ from the construction shown in Fig. 9 and to resemble the construction shown in Fig. 4. In Fig. 10 the original record sheet is indicated as 30, the triplicate record sheet is indicated as 28, and these 30 two are connected along a perforated fold line 26. The triplicate record sheet is provided with a stub portion 46 as is the triplicate record sheet shown in Fig. 7. There is a perforated line of severance 48. The one time carbon sheet 34 is adhesively secured as at 38 to the back of the original record sheet as shown. The unit when made up comprises the two clean surfaced record sheets and the one time carbon sheet which is clean surfaced on one side to receive 45 a record and to this extent resembles the unit of Fig. 9 and also the unit of Fig. 7. It differs from the unit of Fig. 7 in that the one time carbon sheet of Fig. 10 is adhesively secured to one of the record sheets in the unit for detachment with the unit from the book, while in the unit shown in Fig. 7 the one time carbon sheet forms a permanent part of the book cover.

50 These books may be numbered to be used from the top down or from the bottom up and in Fig. 9 the number 7 is shown as applied to the original record sheet 30 and to the second stub of the triplicate record sheet 28. This reference numeral is indicated by the number 54. If the book is to be operated from the bottom up the several sets will be so numbered and the unwritten blank sets will be turned over the front cover and the set of leaves to be written will be positioned over the stop sheet with the heavy duty carbon leaf positioned between the 55 original and duplicate leaves.

55 In the construction shown in the first three figures of the drawing the heavy duty carbon leaf is positioned between the clean surfaced duplicate leaf 32 and the clean surfaced triplicate leaf 28. The one time carbon sheet 34 would imprint the record on the duplicate record leaf 32 and the heavy duty carbon sheet 40 would imprint the same record upon the triplicate record leaf 28.

60 76 In the constructions of Figs. 7, 9 and 10 the

heavy duty carbon sheet 40 would superimpose the clean surface of the one time carbon sheet 34 immediately underneath the original record leaf 30. In these constructions the one time carbon sheet 34 would make the record upon 5 the triplicate record sheet 28.

As hereinabove set forth the identifying number 7, which indicates the number of the sheet and which is identified in the drawings by the reference numeral 54, appears on the secondary 10 stub of the triplicate record sheet 28 underneath the clean surfaced end portion of the transfer-record leaf 34. This transfer-record leaf 34 is of thin paper and as described is very thinly carbonized. The end portion of this transfer-record leaf 34 which overlies the secondary stub of the triplicate leaf 28 is so formed as to be translucent so that the identifying number 7 is readily visible therethrough. After the triplicate record leaf 28 is detached along the line 20 50 from its secondary stub, this stub is left attached to the transfer-record leaf 34 and the identifying number serves also as the identifying number for the transfer-record leaf.

25 The imprinting of the number on the triplicate leaf 28 makes for more convenient and more simple manufacturing operation than to imprint such number on the transfer-record leaf. As has been set forth hereinabove, the number is readily visible through the transfer-record leaf 30 to serve as an identifying number therefor.

30 Following the making of the record upon the first unit the record leaves desired for distribution would be removed from the book. In the construction shown in Fig. 2 the original triplicate and one time carbon sheets might be removed from the unit leaving the duplicate record sheet in the book and this plan would also be followed with the construction shown in Fig. 4. In the construction shown in Fig. 7 the one time carbon sheet would be left in the cover upon detachment of the connected original and triplicate record sheets by severance of the triplicate sheet along the perforated line 26 from its stub 35 40 45 31. In the construction shown in Figs. 9 and 10 all three record sheets might be removed from the cover. In the construction shown in Fig. 9, however, the one time carbon sheet might be left in the cover attached to the secondary stub of the triplicate record sheet and the triplicate record sheet might be severed from the cover 50 along the line 50 instead of along the line 48.

35 In the writing of successive entries the stop sheet will be interposed, assuming the book is being worked from the bottom up as hereinabove described, over the used record sheets remaining in the book. In those constructions which embody the removal of the one time carbon sheet with the record sheets as a part of the unit removed from the cover upon the writing of an 60 entry it is apparent that a subsequent entry may be made in this detached unit though such subsequent entry would not appear from the record sheet in the cover unless it was entered thereon but it would appear upon the two record sheets 65 of the unit which go to separate places for distribution and record. Of course, in constructions such as shown in Figs. 9 and 10 the entry could appear on all three record sheets even though made after the removal of the record sheets from 70 the cover.

40 If the units are numbered from the top down, the procedure would be different merely in that the used record sheets remaining with the cover would be thrown over the front cover of the con- 75

tainer after use and the stop sheet would be interposed over the unused units and underneath the unit being used. If the form of cover shown in Fig. 5 is used the book would necessarily be numbered from the bottom up as there would be no stop sheet to protect the used sets containing one time carbon sheets.

In the construction shown in Fig. 8 the operation would be similar to that described in connection with the other constructions. The difference is that the heavy duty carbon sheet is stitched in the cover with the record sheets and all used record sheets would be removed from the cover following use. For the unit shown in Fig. 9 to be used with one record sheet remaining in the cover it would have to be used in a different type of cover from that shown in Fig. 8. In other words, the heavy duty carbon sheet would have to be mounted differently. It could be mounted as shown in the cover of Fig. 3.

What I claim is:

1. A manifolding book comprising, in combination, a cover, a plurality of manifolding sets secured within the cover, each set including three record leaves, each set including two detachably connected clean surfaced record leaves detachably connected as a set within the cover, and a one time carbon leaf arranged between said record leaves, said carbon leaf being secured to one of the record leaves for detachment from the cover with the set and being detachable from the set without detachment of the other record leaves constituting the set and a heavy duty carbon leaf hingedly secured to a longitudinal margin of the cover and swingable successively into each manifolding set to overlie one of the leaves thereof and to transfer a record written on one of the record leaves of the set onto another record leaf of the set.

2. A manifolding book comprising, in combination, a cover including a swingably stop sheet, a heavy duty carbon leaf swingably connected to the stop sheet to fold thereover, a plurality of manifolding sets bound in the cover, each set including two detachably connected clean surfaced record leaves detachably connected as a set within the cover and a one time carbon leaf disposed between said record leaves, said carbon leaf being secured to one of the record leaves for detachment from the cover therewith upon detachment of the set from the cover, said carbon leaf being detachable from the leaf to which it is secured in the set without detachment of the other leaves in the set, said stop sheet being swingable successively under successive manifolding sets and said heavy duty carbon sheet being swingable into the manifolding set underneath which the stop sheet is positioned.

3. A manifolding book comprising a plurality of manifolding sets, each set including three record receiving leaves, each set including two clean surfaced record leaves and a one time carbon leaf disposed between said record leaves, a cover assembly within which the plurality of manifolding sets are secured, said cover assembly including three sheets hinged end to end, two of said sheets constituting front and back cover sheets, the third sheet constituting a stop sheet swingable successively into position underneath successive manifolding sets, a heavy duty carbon leaf hinged to one longitudinal margin of the stop sheet and swingable into the set underneath which the stop sheet is positioned.

4. A triplicate manifolding book comprising, in combination, a plurality of manifolding sets

arranged within a cover, each set consisting of a clean surfaced triplicate record leaf detachably secured at one end within the cover and having a clean surfaced original leaf detachably connected to the opposite end thereof and adapted to fold thereover, a one time carbon leaf having one clean record receiving surface and disposed within the set to transfer a record written onto the original record leaf onto the triplicate record leaf and itself connected with one of the record leaves for detachment from the cover with the set, and a heavy duty carbon leaf hinged within the cover and swingable successively into successive manifolding sets overlying the clean surface of the one time carbon leaf in the set.

5. A triplicate manifolding book comprising, in combination, a plurality of manifolding sets arranged within a cover, each set consisting of a clean surfaced triplicate record leaf detachably secured at one end within the cover and having a clean surfaced original leaf detachably connected to the opposite end thereof and adapted to fold thereover, a one-time carbon leaf having one clean record receiving surface and disposed within the set to transfer a record written onto the original record leaf onto the triplicate record leaf and itself connected with the back of the original record leaf for detachment therewith upon detachment of the set from the cover or for detachment therewith from the triplicate record leaf, and a heavy duty carbon leaf hinged to the cover and swingable successively into successive manifolding sets overlying the clean surface of the one time carbon leaf.

6. A triplicate manifolding book comprising, in combination, a plurality of manifolding sets arranged within a cover, each set consisting of a clean surfaced triplicate record leaf detachably secured at one end within the cover and having a clean surfaced original leaf detachably connected to the opposite end thereof and adapted to fold thereover, a one time carbon leaf having one clean record receiving surface and disposed within the set to transfer a record written onto the original record leaf onto the triplicate record leaf and itself connected with the triplicate record leaf adjacent to its line of detachment from the cover, said triplicate record leaf provided with a second line of detachment substantially parallel to the first line of detachment and spaced outwardly toward the free end of the leaf therefrom and beyond the line of attachment of the one time carbon leaf thereto, and a heavy duty carbon leaf hinged within the cover and swingable successively into the successive manifolding sets overlying the clean surface of the one time carbon leaf.

7. A cover for a manifolding book comprising a back, a front cover hinged to one end of the back to fold thereover, a stop sheet hinged to the opposite end of the back to fold thereover, and a heavy duty carbon sheet hinged to one longitudinal margin of the stop sheet to fold thereover.

8. A triplicate manifolding book comprising, in combination, a plurality of manifolding sets arranged within a cover, each set consisting of a clean surfaced triplicate record leaf detachably secured at one end within the cover and having a clean surfaced original leaf detachably connected to the opposite end thereof and adapted to fold thereover, said triplicate record leaf provided with two parallel spaced apart weakened lines of detachment disposed adjacent to the end of the leaf that is secured to the cover, a one-time carbon leaf having one clean record receiv-

ing surface and being disposed between said triplicate record leaf and the original record leaf and connected at one end with the triplicate record leaf within the space between said two parallel lines of detachment, said cover comprising three leaves connected end to end, two of said leaves constituting the front and back cover sheets and

the third leaf constituting a stop sheet and a heavy duty carbon leaf hinged to said stop sheet and swingable successively into successive manifolding sets overlying the clean surface of the one-time-carbon leaf.

5

ALBERT R. LAWSON.
